DESIGN FOR A TOY CANNON

Douglas C. La Barre, Santa Monica, Calif.

Application July 3, 1945, Serial No. 120,487

Term of patent 14 years

(Cl. D34—15)

To all whom it may concern:

Be it known that I, Douglas C. La Barre, a citizen of the United States, residing in the city of Santa Monica, county of Los Angeles, and State of California, have invented a new, original, and ornamental Design for a Toy Cannon, of which the following is a specification, reference being had to the accompanying drawing, forming a part thereof.

Fig. 1 is a side elevation of the toy cannon showing my new design; Fig. 2 is a top plan view of the toy cannon; and Fig. 3 is a front elevational view of the toy cannon.

I claim:

The ornamental design for a toy cannon, as shown.

DOUGLAS C. LA BARRE.
